DESIGN FOR A BARBED WIRE SUPPORTING ARM FOR FENCES

William A. Webster, Wilmar, Calif., assignor to
Southern California Fence Co., a corporation of
California

Application June 11, 1946, Serial No. 130,639

Term of patent 3½ years

(Cl. D28—1)

To all whom it may concern:

Be it known that I, William A. Webster, a citizen of the United States and residing at Wilmar, in the county of Los Angeles, State of California, have invented a new, original, and ornamental Design for Barbed Wire Supporting Arm for Fences, of which the following is a specification, reference being had to the accompanying drawing, forming part thereof, in which:

Fig. 1 is a side elevation of a barbed wire supporting arm for fences showing my new design,

Fig. 2 is a top plan view thereof, and

Fig. 3 is a perspective view of the arm looking upward from one side thereof.

I claim:

The ornamental design for a barbed wire supporting arm for fences, substantially as shown.

WILLIAM A. WEBSTER.
